his Attorney.

UNITED STATES PATENT OFFICE

2,309,547

GUIDING DEVICE

Robert J. Stoker, Gary, Ind., assignor to Carnegie-Illinois Steel Corporation, a corporation of New Jersey

Application June 26, 1941, Serial No. 399,922

4 Claims. (Cl. 271—59)

This invention relates to guiding devices, and more particularly to those which are used for guiding the side edges of sheets, strip, etc.

In the manufacture of strip metal, it is frequently necessary to employ side guides in order to eliminate transverse shifting. Such devices frequently take the form of holders disposed at either side edge of the strip or sheet and carrying a rigid wearing plate for contact therewith. The wearing plates are usually quite rigid, and because of this frequently cause the side edges of the strip or sheet to "curl" or otherwise be damaged. This is particularly true with respect to the ends of the strip or sheet.

In lieu of guiding devices of the type described immediately hereinbefore, it has been proposed to utilize apparatus embodying springs or other resilient instrumentalities, but so far as I am aware these apparatus are expensive and troublesome to manufacture, install and operate.

It is among the objects of the present invention to provide an efficient but inexpensive device for guiding the side edges of strip, sheet, etc., which is characterized by sufficient resiliency to eliminate damage.

Another object is the provision of a device of the class described which is so constructed as to be susceptible to employment in connection with other apparatus of existing design.

The foregoing and other objects will become more apparent after referring to the drawing, in which:

Figure 1 is a side elevation of the device of the present invention.

Figures 2 and 3 are end views on the lines II—II and III—III, respectively, of Figure 1.

Figure 4 is a sectional view on the line IV—IV of Figure 1, and illustrates the manner in which the device is secured to a guiding bed or table in its sheet or strip guiding capacity.

Referring more particularly to the drawing, the device of the present invention comprises a holder which includes a supporting member 2 in the form of a substantially rectangular block having considerably greater height than width and carrying at its upper end a right angularly extending overhanging flange 3. Along its lower end, but disposed in offset relationship with respect to the center-line of the rectangular block, is a right angularly extending outboard lug 4 which is substantially rectangular in cross section. The right angularly extending outboard lug 4 is adapted to seat in and be moved along an inverted T-shaped recess 7 of a conventional guiding bed or table 8. Extending through this

outboard lug 4 and through the supporting member 2 is an aperture 10 which receives a bolt 11 having a head 13 with seats in the bottom of the inverted T-shaped recess 7 of the guiding bed or table 8. The upper end of the bolt 11 projects above the supporting member 2 and is screw-threaded in the customary manner, and carries a nut 14 whereby the bolt 11 may be elevated sufficiently to permit the inner face of its head 13 to come into clamping contact with the upper face of the bottom of the inverted T-shaped recess 7 to thus maintain the supporting member 2 in rigid relationship on the guiding bed or table 8.

Referring more particularly to Figure 4, the numeral 15 generally designates a spacer member which comprises a substantially rectangular block having considerably greater height than width and carrying at its upper end a right angularly extending overhanging flange 16. Thus the spacer member 15 is shaped similarly to the supporting member which is described hereinbefore. The spacer member 15 is disposed similarly to the supporting member 2 and in spaced parallelism with respect thereto, whereby its overhanging flange 16 lies immediately below the overhanging flange 3 of the said supporting member.

As shown more clearly in Figures 2 and 4, the supporting member 2 and the spacer member 15 are welded together adjacent their end portions to provide a clearance space 17 which extends continuously upwardly and horizontally between the overhanging flanges 3 and 16 of the said supporting member 2 and spacer member 15 respectively. At their other ends the space between the supporting member 2 and spacer member 15 are closed by a continuous weld 20, as clearly shown in Figure 3.

The guiding instrumentality per se comprises an inverted U-shaped metallic strip 21 one leg of which is fore-shortened as shown at 22. This guiding instrumentality 21 is formed of a suitable strip of wear-resistant alloy, of which there are so many materials well known to the art as not to require enumeration herein.

According to the foregoing construction and arrangement, the guiding instrumentality 21 may be slid between the supporting member 2 and spacer member 15 from the ends thereof which are connected by the weld 17. The sliding movement is continued until the advance end of the guiding instrumentality 21 contacts the continuous weld 20 at the opposite ends of the supporting member 2 and spacer member 15.

In practice, the supporting member 2 and

spacer member 15 are so disposed that the continuous weld 20 is at the ends thereof through which the strip or sheet being guided emerges, whereby the movement of the strip or sheet will not displace the guiding instrumentality 21.

As shown more clearly in Figure 4, the long leg of the guiding instrumentality 21 provides a space between it and the adjacent face of the spacer member 15 to permit of some deflection outwardly with respect to the strip to accommodate irregularities, etc., without causing "curling" or other damage to the strip or sheet.

While I have shown and described one specific embodiment of the present invention, it will be seen that I do not wish to be limited exactly thereto, since various modifications may be made without departing from the scope of the invention as defined in the appended claims.

I claim:

1. A guide device for contacting the edge of a horizontally moving sheet or the like, comprising a vertically-extending supporting member carrying a lateral flange in spaced relation from the bottom thereof, and a flexible strip depending from said flange and disposed in spaced relationship with respect to said wall, whereby said flexible strip may be displaced toward said vertically-extending supporting member by the contact therewith of the edge of the sheet being guided, said flexible strip having a lateral flange underlying the lateral flange aforesaid, the lateral flange of said flexible strip being maintained in position against the lateral flange of said vertically-extending supporting member.

2. A guide device for contacting the edge of a horizontally moving sheet or the like, comprising a vertically extending supporting member carrying a lateral flange in spaced relation from the bottom thereof, and a flexible strip depending from said flange and disposed in spaced relationship with respect to said wall, whereby said flexible strip may be displaced toward said vertically-

extending supporting member by the contact therewith of the edge of the sheet being guided, said flexible strip having a lateral flange underlying the lateral flange aforesaid, the lateral flange of said flexible strip being detachably secured to the lateral flange of said vertically extending supporting member.

3. A guide device for contacting the edge of a horizontally moving sheet or the like, comprising a supporting member defining a substantially vertical wall facing the sheet and carrying a flange overhanging the top of said wall, a spacer member underlying the overhanging flange of said supporting member, and a flexible strip depending from the overhanging flange of said supporting member, said flexible strip being provided with an angular portion disposed between said spacer member and the under side of the overhanging flange of said supporting member, the outer face of said spacer member being spaced from said flexible strip whereby the latter may be displaced in that direction by contact with the edge of the sheet being guided.

4. A guide device for contacting the edge of a horizontally moving sheet or the like, comprising a supporting member defining a substantially vertical wall facing the sheet and carrying a flange overhanging the top of said wall, a spacer member underlying the overhanging flange of said supporting member, said spacer member being provided with a flange in parallelism with the flange of said supporting member, and a flexible strip depending from the overhanging flange of said supporting member, said flexible strip being provided with an angular portion disposed between the flanges of said spacer member and said supporting member, the outer face of said spacer member being spaced from said flexible strip whereby the latter may be displaced in that direction by contact with the edge of the sheet being guided.

ROBERT J. STOKER.
